SELF-FEEDING STOVE

Henry B. Crowell, Hoquiam, Wash.

Application April 14, 1941, Serial No. 388,523

1 Claim. (Cl. 126—73)

This invention relates to new and useful improvements in stoves and a specially wood-burning stove, the principal object of the invention being to provide a stove constructed in such a manner that the stove can be stocked with fuel which will feed downwardly into the fire area or draft line as the underlying fuel is consumed.

Another important object of the invention is to provide a stove construction which will burn fuel over a considerable period of time without restocking or replenishment of the fuel.

Other objects and advantages of the invention will become apparent to the reader of the following specification.

In the drawings:

Figure 1 represents a top plan view of the stove.

Figure 2 is a vertical sectional view through the stove.

Figure 3 is a horizontal sectional view taken substantially on the line 3—3 of Figure 2.

Referring to the drawings wherein like numerals designate like parts, it can be seen that numeral 5 denotes an outside shell supported by legs 6 and having a perforated top 7.

Numerical 8 denotes an inside shell, while inside of the inside shell 8 is a fire and storage box 9 which may have an opening adjacent the top thereof and a door in the upper portion of the shell 5 through which fuel can be inserted.

A vertically disposed partition 10 is provided in the inner shell 8 adjacent one side thereof to define a passageway 11. This partition 10 having an opening 12 adjacent its lower end to communicate the passageway 11 with the chamber 13 surrounding the fire and storage box 9. From the upper end of the shell 8 and extending through an opening in the upper portion of the shell 5 and being in communication at its inner end with the passageway 11 is a flue attaching neck 14 having a damper 15 therein.

The lower portion of the box 9 has a grate 16 therein upon which the burning wood 17 is located and upon this burning wood is a stock of fuel or wood 18 which will burn as the mass 17 is consumed. This mass 17 is within the path of a draft which extends through openings 19 and 20 in diametrically opposite side portions of the box 9. As can be seen in Figures 2 and 3, the inner shell 8 is in spaced relation with respect to the outer shell 5 to define a chamber 21. Air admission louvres 22 are provided in one side of the outer shell 5 so as to admit air to the chamber 21. Additional louvres 23 are provided in the diametrically opposite wall of the shell 5 to also admit air to the chamber 21 and additional air louvres 24 are provided in the upper portion of the shell 5.

It can be seen that air entering the louvres 22,

23 will pass through the opening 19 and through the mass of burning fuel 17, through the opening 20 to the space 13. The hot fumes pass around and over the box 9 and down to the opening 12 in the partition 10, thus conserving as much heat as possible before rising in the space 11 to the flue attached neck 14, and, of course, this passage of air and hot fumes is regulated by the damper 15, and if desired another damper may be provided at the air admission opening 19 to the fire box.

An ash receiving drawer 25 is provided below the grate 16. Obviously, suitable doors can be provided for the firebox and for the ash drawer 25 as well as for the upper portions of the box 9 so that fuel can be placed in the box.

Obviously, the draft in crossing the grate and passing through the fire bed carries with it, the hot fumes of combustion. These fumes must pass up and around the inner shell and downwardly to reach the flue opening at the lower portion of the outer shell and at the back portion thereof. Thus, the heat has time to radiate to an efficient extent.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A stove comprising an outer shell having an air inlet opening at the lower portion thereof and an air outlet opening at the upper portion thereof, an inner shell located within the outer shell and being spaced at its sides and top from the outer shell to define an air passageway from the air inlet opening to the air outlet opening, a fire and fuel storage box located within the inner shell and being spaced at its sides and top from said inner shell to define a passageway for the hot products of combustion, a vertically disposed partition in the space between the box and the inner shell, extending downwardly from the top of the inner shell and having an opening at its lower end, said partition being spaced both from the inner shell and the box to define a tortuous passageway for the hot products of combustion, an outlet pipe extending from the upper portion of the inner shell in opposed relation to the upper portion of the partition, a grate in the lower portion of the box, the side portion of the box opposite from the side to which the partition is opposed being formed with a hot products of combustion outlet.

HENRY B. CROWELL.
